United States Patent Office

Des. 185,305
Patented May 26, 1959

185,305

TABLE

Charles P. Molla, Westbury, N.Y.

Application September 9, 1957, Serial No. 47,663

Term of patent 14 years

(Cl. D33—14)

FIG. 1

Fig. 2

Fig. 1 is an isometric perspective view of a table; and Fig. 2 is a plan view of the table top with the characterizations shown dark rather than light as appearing in Fig. 1.

I claim:

The ornamental design for a table, as shown.
